(57) **CLAIM**

The ornamental design for an base, as shown and described.

DESCRIPTION

FIG. 1 is a top perspective view of a base, showing my new design in an environment of use with a dice tower fixed to the top surface thereof;

FIG. 2 is a top perspective view thereof, illustrated with the environmental dice tower omitted for clarity of disclosure;

FIG. 3 is a bottom perspective view of FIG. 2;

FIG. 4 is a top plan view of FIG. 2;

FIG. 5 is a bottom plan view of FIG. 2;

FIG. 6 is a front elevational view of FIG. 2, the rear elevational view being a mirror image thereof and therefore not shown; and,

FIG. 7 is a left-side elevational view of FIG. 2, the right-side elevational view being a mirror image thereof and therefore not shown.

The broken lines in FIG. 1 showing a dice tower represent environmental matter that forms no part of the claimed design. The broken lines immediately adjacent the shaded surfaces depict the bounds of the claimed design, whereas all remaining broken lines in the figures depict portions of the base, all of which form no part of the claimed design.
